CLAIM

The ornamental design for a wine flight carrier, as shown and described.

DESCRIPTION

FIG. 1 is a front, top perspective view of my new design, carrying wine glasses;

FIG. 2 is a front, top perspective view of my new design;

FIG. 3 is a top plan view of the design of FIG. 2;

FIG. 4 is a bottom plan view of the design of FIG. 2;

FIG. 5 is a rear elevation view of the design of FIG. 2;

FIG. 6 is a front elevation view of the design of FIG. 2; and,

FIG. 7 is a side elevation view of the design of FIG. 2. The opposing side elevation is a mirror image thereof.

The broken lines in the figures are for illustrative purposes only and form no part of the claimed design.
